UNITED STATES PATENT OFFICE.

CHARLES R. LEIMECKE, OF DETROIT, MICHIGAN; BLANCHE C. LEIMECKE, WIDOW OF SAID CHARLES R. LEIMECKE, DECEASED.

LIGHTING-FIXTURE.

1,399,062.

Specification of Letters Patent.

Patented Dec. 6, 1921.

Application filed May 27, 1920. Serial No. 384,600.

To all whom it may concern:

Be it known that I, CHARLES R. LEIMECKE, a citizen of the United States, residing at Detroit, Michigan, have invented a certain 5 new and useful Improvement in Lighting-Fixtures, of which the following is a full, clear, and exact description, such as will enable others skilled in the art to which it appertains to make and use the same, reference being had to the accompanying drawings, forming part of this specification.

My invention relates generally to devices for the distribution of artificial light, and more particularly to that type of device 15 known as a semi-direct lighting fixture, and which latter, it will be understood, is designed for the purpose of utilizing to the best advantage, the reflected rays of practically all the light produced by the electric lamp or other source of light associated 20 with the fixture, and to effect a uniform distribution of such reflected light rays.

The principal objects of my invention are, to provide a relatively simple lighting fixture, 25 the construction of which is such that it may be easily and cheaply manufactured and readily assembled or taken apart; and, further, to provide a fixture wherein the entire lower portion including the reflectors, 30 the source of light, and bowl are not only adjustable with respect to each other but are capable of being bodily raised or lowered in order to obtain the desired or correct illumination and also to obtain proper 35 diffusion of all of the direct and reflected rays from the source of light associated with the fixture.

Further objects of my invention are, to provide a lighting fixture with a semi-focusing reflector that is disposed between the source of light and the main reflector, which semi-focusing reflector is composed in part 40 of clear or transparent glass and partly of translucent glass, the latter being disposed 45 so as to prevent direct rays from the source of light from reaching the main reflecting surface of the fixture, and, further, to arrange the reflectors and bowl so that electric lamps of different sizes may be interchangeably used in the fixture and the bowl being mounted so that it may be swung to one side and upwardly without interfering with other parts of the fixture in order to permit 50 the ready installation or removal of a lamp

or for the purpose of cleaning said bowl, the 55 parts of the fixture, or the lamp that is positioned therein.

With the foregoing and other objects in view, my invention consists in certain novel features of construction and arrangement of 60 parts, hereinafter more fully described and claimed, and illustrated in the accompanying drawings, in which—

Figure 1 is a vertical section taken through the center of a lighting fixture of 65 my improved construction.

Fig. 2 is a plan view of a bridge plate that serves as a support and connecting member for the various parts of my improved fixture.

Fig. 3 is a plan view of the plate that is secured to the ceiling immediately over the outlet box therein and which plate forms a support for the fixture.

Fig. 4 is an elevational view of the fixture 75 with the adjustable parts in elevated position and with dotted lines showing a bowl tilted to permit the insertion or removal of a lamp or for the purpose of cleaning said lamp or the lower portion of the fixture. 80

Fig. 5 is an enlarged vertical section taken approximately on the line 5—5 of Fig. 4.

Fig. 6 is a detail section illustrating a buffer spring against which the edge of the bowl engages when the same is shifted to 85 permit the insertion or removal of a lamp or for the purpose of cleaning said lamp or fixture.

Fig. 7 is an elevational view of a modified form of my improved lighting fixture where- 90 in the main body portion of the fixture is suspended a substantial distance below the ceiling.

Fig. 8 is an elevational view partly in section of a form of fixture that is suspended 95 directly beneath the ceiling.

Referring by numerals to the accompanying drawings, and particularly to the construction illustrated in Figs. 1 to 6 inclusive, 10 designates a plate preferably of 100 metal that is secured in any suitable manner directly to the ceiling or to an outlet box located in the ceiling and secured in any suitable manner to said plate and inclosing the same is a ring 11, preferably formed of sheet 105 metal and provided in its lower end with an opening 12.

Secured to plate 10 is a depending cylin-

cylindrical member 13 that extends through opening 12 and secured to and depending from the center of plate 10 and centrally located within said member 13 is a rod 14. Arranged for sliding movement on this rod is a substantially rectangular frame 15, and positioned on the rod above this frame is a buffer spring 16 that is adapted to break the force of the upward movement of frame 15 when the lower portion of the fixture is drawn downward to its limit of movement.

Secured to frame 15 is a collar 17 through which rod 14 passes, and seated in said collar is a set screw 18 by means of which the collar and frame may be locked to the rod after vertical adjustment thereupon.

Arranged for vertical sliding movement upon cylindrical member 13 is a sleeve 19, preferably of sheet metal, the lower portion of which is provided with an outwardly projecting depending ornamental flange 20, and the lower portion of the latter is provided with a plurality of short vertically disposed slots 21 that are arranged preferably at ninety degrees apart.

Positioned in the space within flange 20 is a bridge plate comprising a ring-shaped body portion 22 from which projects a plurality of radially disposed arms 23, the latter being arranged preferably at ninety degrees apart and the outer portions of these arms project through the slot 21 in flange 20. Projecting upwardly from the outer ends of arms 23 are threaded pins 23^a, and positioned thereupon are outwardly projecting hooks 24 that are retained in position by nuts 25.

Formed in the ring-shaped body 22 of the bridge plate and preferably at diametrically disposed points are slots 26, the inner ends of which terminate in laterally projecting notches 27, and passing through these notches are the ends of flexible members 28 such as cables or chains. Secured to the ends of these flexible members and bearing against the underside of the ring 22 are small blocks 29. The flexible members 28 pass over pulleys 30 that are journaled in suitable bearings that depend from ceiling plate 10 and the corresponding ends of said flexible members are secured in any suitable manner to ears 15^a which project laterally from the frame 15.

Depending from ceiling ring 10 and arranged preferably at right angles to the pulleys 30 are guide rods 31 and arranged to slide thereupon are tubular members 32 that are fixed to and project upwardly from the ring-shaped body portion 22 of the bridge. The construction just described is effective in guiding the bridge plate and parts carried thereby during its vertical movement and holding said parts firmly against lateral swinging movement.

Suspended in any suitable manner from

the hooks 24 is the main reflector of my improved lighting fixture, the same being constructed of porcelain, glass, or metal having a polished reflecting surface, and said member being in the form of a ring having a flat 70 horizontally disposed inner portion 33 and a downwardly curved outer portion 34.

Depending from the members of an oppositely disposed pair of the arms 23 are rods 35, and arranged for adjustment on 75 the upper portions thereof and to be locked thereto after adjustment by means of set screws 36 are collars 37. Supported by these collars 37 is an inner secondary reflector constructed from metal, porcelain, or any 80 desired material, and the body thereof comprises a substantially horizontal outer portion 38, the outer edge thereof terminating in a vertically disposed flange 39, and the inner portion being curved inwardly and 85 downwardly as designated by 40. The horizontally disposed portion 38 is provided with suitable perforations which receive the supporting rods 35 and the upstanding flange 39 projects upwardly through the 90 opening in the center of the main reflector.

The surface of the inwardly curved portion 40 of this inner or secondary reflector combines with the under surfaces of the portions 38 and 33, and the under surface of 95 portion 34 of the main reflector to form a substantially parabolic reflecting surface that is effective in deflecting light rays outwardly and downwardly.

Secured in any suitable manner to the 100 top of the secondary reflector and immediately over the opening in the center thereof is a socket 41 to which lead suitable electrical conductors and said socket being adapted to receive an electric lamp such as 105 42. Positioned on the lower portions of rods 35 are collars 43 that are adapted to be locked to said rods by set screws 44 and depending from said collars are hooks 45. Suspended by means of suitable links 46 110 from these hooks 45 is an open-topped bowl 47, preferably of glass, and the top of this bowl occupies a horizontal plane a short distance below the plane occupied by the lower edge of the main reflector comprising 115 the parts 33 and 34.

Positioned within the open upper end of the bowl 47 and immediately below the center or secondary reflector comprising the parts 38 and 40 is a semi-focusing reflector, 120 preferably constructed of glass, and of substantially flat conical or bell-shape. The upper end of this semi-focusing reflector terminates in a tubular neck 48 that projects upwardly into the opening that is 125 formed in the center of the secondary reflector, and the outer face of said neck being provided with a plurality of annular grooves 49 which are adapted to receive the inner ends of set screws 50 the latter pass- 130

ing through the lower portion of the inwardly curved wall 40.

By virtue of the construction just described, the semi-focusing reflector may be 5 adjusted vertically with respect to the center or secondary reflector and likewise with respect to the lamp that is seated in and depends from the socket 41. That portion of the semi-focusing reflector immediately beneath 10 the tubular neck 48 is curved outwardly and downwardly as designated by 51 and this particular portion is formed of clear or transparent glass and the lower portion 52 of this semi-focusing reflector or that 15 portion which depends from the portion 51 is formed of translucent glass, and as a result, the direct rays of light from the filament or lamp 42 are prevented from striking the reflecting surface of the portion 34 20 of the main reflector.

The lower portion of the fixture including the reflectors, the lamp, and the bowl can be adjusted vertically by raising or lowering said lower portion to the desired horizontal 25 plane, and after proper adjustment, collar 17 is locked to rod 14 by tightening set screw 18, thereby effectually holding the entire lower portion of the fixture in its adjusted position.

30 During the vertical movement of the lower portion of the fixture, the bridge comprising the parts 22 and 23 is guided and firmly held by the engagement of rods 31 in tubes 32, and as a result, the lower portions 35 of the fixture are held against lateral swinging movement.

The vertical positions of the inner or central reflector comprising parts 38 and 40, the semi-focusing reflector, and the lamp can be 40 adjusted by raising or lowering the collars 37 upon rods 35 and which collars support the secondary or central reflector. The semi-focusing reflector can be independently adjusted vertically by moving the collar 48 45 upwardly or downwardly through the opening in the central reflector and locking said semi-focusing reflector after adjustment by proper manipulation of the set screws 50, the inner ends of which latter are adapted 50 to engage in the grooves 49.

Bowl 47 can be adjusted vertically with respect to the lamp 42 and the semi-focusing reflector by raising or lowering the collars 43 from which said bowl is supported and 55 said collars being locked to rods 35 by set screws 44.

Thus the entire lower portion of the fixture can be raised or lowered as a unit and in order to insure proper distribution of 60 reflected light from the lamp and to obtain a maximum degree of efficiency or lighting effect from the fixture, the lamp and central reflector, the semi-focusing reflector, and the bowl are vertically adjustable with respect 65 to each other.

The position of the semi-focusing reflector and the arrangement of the clear and translucent portions thereof permits direct rays from the lamp to pass directly upward and outward onto the reflecting surfaces of the 70 portions 38 and 40 of the center reflector, but prevents direct light rays from passing onto the reflecting surfaces of the portions 33 and 34 of the outer or main reflector. As a result of this arrangement, practically all of 75 the light rays passing in an upward direction from the source of light contact either directly or indirectly with the reflector comprising the reflecting surfaces of the parts 33, 34, 38 and 40 and by said surfaces, these 80 light rays are reflected downwardly and outwardly from the fixture to combine with the light rays which pass downwardly and outwardly through the translucent bowl 47.

When it is desired to replace the lamp or 85 clean the lamp that is positioned in the fixture or to clean the interior of the bowl 47 or the interior of the semi-focusing reflector, bowl 47 is tilted into the position shown by dotted lines in Fig. 4, during which tilting 90 movement the links 46 swing upon the hooks 45 and in order to protect the inner or secondary reflector from injury as a result of contact with the upper edge of the bowl, a relatively small light spring such as a, Fig. 95 6, is secured to the under side of portion 38 of said inner or secondary reflector to act as a buffer for the edge of the bowl when the latter is swung upwardly.

In Fig. 7 I have shown my improved fixture as being suspended a substantial distance below the ceiling and where this is done, the means utilized for effecting vertical adjustment of the entire lower portion of the bowl is eliminated and the portion 105 of a suitable ornamental hanger such as A, Fig. 7, is connected directly to the sleeve 19.

In Fig. 8 I have illustrated a modified construction wherein the fixture is adapted to be positioned immediately adjacent to the 110 ceiling and said fixture being devoid of the arrangements for adjusting its entire lower portion as a unit.

A lighting fixture of my improved construction is comparatively simple, is capable 115 of being readily assembled or taken apart, and by virtue of its various adjustments, it is possible to obtain maximum efficiency of practically all the light rays emanating from the lamp or source of light used in connection with the fixture.

I claim as my invention:

1. In a lighting fixture, the combination of a vertically adjustable outer reflector having a reflecting surface, an extension forming a secondary or inner reflector also having a reflecting surface and which is arranged for vertical adjustment independently of 125 said outer reflector, a bowl suspended beneath said inner reflector, a source of light 130

within said bowl, and a semi-focusing reflector arranged between said source of light and said outer reflector.

2. In a lighting fixture, a reflector, a bowl suspended beneath said reflector, there being an open space between the top of said bowl and the reflecting surface of said reflector, a source of light within said bowl, and a semi-focusing reflector disposed between said source of light and the reflector, which semi-focusing reflector is provided with a clear or transparent upper portion and a translucent lower portion.

3. In a lighting fixture, a reflector, a bowl suspended beneath said reflector, there being an open space between the top of said bowl and the reflecting surface of said reflector, a source of light within said bowl, a semi-focusing reflector disposed between said source of light and the reflector, which semi-focusing reflector is provided with a clear or transparent upper portion and a translucent lower portion, and said semi-focusing reflector being vertically adjustable with respect to said bowl.

4. In a lighting fixture, a reflector comprising inner and outer portions, the inner portion being vertically adjustable independently of the outer portion, a semi-focusing reflector carried by said adjustable inner portion, a source of light immediately below said semi-focusing reflector, and a bowl suspended in position beneath said semi-focusing reflector and said source of light.

5. In a lighting fixture, a reflector comprising inner and outer portions, the inner portion being vertically adjustable independently of the outer portion, a semi-focusing reflector carried by said adjustable inner portion, a source of light immediately below said semi-focusing reflector, a bowl suspended in position beneath said semi-focusing reflector and said source of light, and which bowl is vertically adjustable with respect to said reflector.

6. In a lighting fixture, a reflector comprising inner and outer parts, the inner part being mounted for vertical adjustment independently of the outer part, a socket carried by said inner part and adapted to receive a lamp, and a semi-focusing reflector carried by said inner part.

7. In a lighting fixture, a reflector comprising inner and outer parts, the inner part being mounted for vertical adjustment independently of the other part, a socket carried by said inner part and adapted to receive a lamp, and an independently adjustable semi-focusing reflector carried by said inner part.

8. In a lighting fixture, a supporting mem-

ber, an outer annular reflector carried thereby, a second inner reflector arranged within said annular reflector and coöperating therewith to form an extension of the reflecting surface thereof, a semi-focusing reflector carried by and depending from the inner reflector, a source of light immediately below said semi-focusing reflector, and a bowl suspended below said semi-focusing reflector and source of light.

9. In a lighting fixture, a supporting member designed to be fixedly attached to the ceiling, a reflector comprising an outer and an inner member, the latter being vertically adjustable with respect to said outer member and the supporting member, a source of light carried by and depending from said inner member, a vertically adjustable bowl suspended from the supporting member and partially inclosing said source of light, and a semi-focusing reflector arranged between the source of light and the outer member of said reflector.

10. In a lighting fixture, the combination with a reflector with a source of light disposed beneath the same, of a semi-focusing reflector disposed between said reflector and source of light, and said semi-focusing reflector being mounted for vertical adjustment with respect to said source of light and reflector.

11. In a lighting fixture, the combination with a reflector with a source of light disposed beneath the same, of a semi-focusing reflector disposed between said reflector and source of light, and said semi-focusing reflector being provided with a clear or transparent upper portion and with a translucent lower portion.

12. In a vertically adjustable lighting fixture, a reflector included therein, a bowl suspended beneath said reflector, means for mounting said bowl and its connected parts whereby they may be rocked to elevate one edge and lower the opposite edge, a cushion spring on the reflector for absorbing shocks, when said bowl is rocked, and a source of light arranged below said reflector and within said bowl.

13. In a lighting fixture, a vertically adjustable reflector, a bowl suspended beneath said reflector and mounted so as to be rocked to elevate one edge and lower the opposite edge, a source of light arranged below said reflector and within said bowl, and a semi-focusing reflector arranged between said source of light and the reflector.

In testimony whereof I hereunto affix my signature this 22nd day of May, 1920.

C. R. LEIMECKE.
